UNITED STATES PATENT OFFICE

144,225

DESIGN FOR A FOOD CHOPPER OR SIMILAR ARTICLE

James Teague, Chicago, Ill., assignor to Wilson Specialties, Inc., Chicago, Ill., a corporation of Illinois

Application September 1, 1945, Serial No. 121,785

Term of patent 14 years

(Cl. D89—1)

To all whom it may concern:

Be it known that I, James Teague, a citizen of the United States and a resident of the city of Chicago, in the county of Cook and State of Illinois, have invented a new, original, and ornamental Design for a Food Chopper or Similar Article, of which the following is a specification, reference being had to the accompanying drawing, forming a part thereof.

On the drawing:

Figure 1 is an elevational view of the food chopper, or similar article, showing my new design, and

I claim:

The ornamental design for a food chopper, or similar article as shown.

JAMES TEAGUE.
